MONOGRAM

Michael Chernow, Brooklyn, N. Y.

Application August 2, 1933. Serial No. 683,248

3 Claims. (Cl. 40—140)

My present invention relates to improvements in monograms of the character which are formed as individual units and then bodily applied to a support surface.

5 The term "monogram" is used for descriptive convenience only and is intended to include letters, numerals, symbols, decorative devices or identifying characters or indicia of any nature whatsoever. The so-called support member to 10 which the monograms are applied may form part of any of an infinite variety of devices, typical examples of which are cigarette cases, vanity cases, escutcheon plates, automobile doors, rings, plaques of glass, celluloid or metal etc.

15 An object of the invention is to provide a monogram which will, when applied, realistically simulate an inlay.

Another object is to provide a monogram adapted to be adhesively secured to the support by a non-water solvent adhesive material permanently carried by the monogram so that the monograms when attached to a support may be exposed to the weather without danger of dislodgement. Furthermore the adhesively coated 25 monograms may be kept in stock indefinitely without deterioration of the adhesive.

Another object is to provide a metal monogram with adhesive material so arranged on its back that when the adhesive is treated with a solvent 30 and the monogram pressed against its support, it will adhere tenaciously not only because of the adhesive qualities of the cement but because of the fact that the adhesive is so applied that it forms ridges defining one or more suction pockets which strongly oppose removal of the monogram. Typically such pockets are formed by a 35 ridge of adhesive material which follows the contour of the monogram and coats with the thinner layer of adhesive on the body of the monogram to afford a sealed pocket when all of the edges of the monogram are pressed into contact with its support surface.

Another object is to provide a monogram which is extremely difficult to pry loose from its support due to the fact that the metal of the monogram is so thin and the adhesive material is so thin that they offer no edge surface which may be struck a hammer blow and the adhesive filled space between the edges of the monogram and 50 the support surface is so extremely thin that it is difficult to wedge even a sharp edged tool between the monogram and support.

Another object of the invention is to provide a monogram inherently capable of clinging to its 55 support surface even though said surface itself

be slightly flexed and a monogram which is extremely unlikely to become loosened from its support by striking against extraneous objects or by careless handling of the monogram bearing article.

Another object is to provide a monogram which may be applied upon any suitable support with expedition and facility and without requiring the use of tools and without the need for any special care or expert handling.

Other objects are to apply a monogram of extremely simple, practical, rugged, durable, inexpensive construction which will be extremely neat and attractive in appearance and which though made of base metal, will when in applied position simulate an expensive precious metal inlay.

In accordance with a preferred embodiment of the invention the monograms are made of extremely thin bendable metal. They may be stamped, but are preferably etched from metal stock of a thickness in the order of not more than .005 to .015 inches. A very thin layer of non-water soluble adhesive or cement is applied to the backs of the monograms in such a fashion that ridges in the adhesive material coat to define one or more pockets. A typical arrangement is to provide a ridge of adhesive material which follows the entire periphery of the monogram and is elevated with respect to the thinner layer of adhesive covering the main body portion of the monogram or a series of criss-crossing ridges when cooperatively defining a series of such pockets.

The monograms with their coated backs may be 90 kept in stock indefinitely by a retailer who applies them as required, to the articles of merchandise which he may be selling. In order to apply them, it is merely necessary to brush them lightly with a solvent for the adhesive and press them manually against the support upon which they are to be mounted. This manual pressure is sufficient to cause all of the adhesive ridges to firmly adhere to the support and to define between the ridges evacuated spaces of minute thickness which insure a suction cup action supplementing the action of the adhesive material itself in restraining the monograms against inadvertent dislodgement.

On the other hand, if it becomes desirable to interchange monograms, the introduction of an extremely sharp pointed instrument to break the seal, permits the monograms to be readily stripped from their support.

When these extremely thin monograms are 110

mounted upon a contrastingly colored background, a most realistic simulation of an inlay is obtained, that is to say, the thickness of the monograms at their edges is so negligible that they appear to be actually embedded in the article upon the surface of which they are mounted.

In the present application I have claimed only the special suction cup effect obtained by the novel method of arranging the adhesive and regardless of whether this adhesive be applied to a thin initial or a thick one, all of the remaining subject matter herein disclosed being claimed in an application entitled "Monogram", filed September 19th, 1933, which is a continuation in part of this application.

The invention may be more fully understood from the following description in connection with the accompanying drawing wherein:—

Fig. 1 is a perspective view of a metal cigarette case with certain of my improved monogram forming characters and a decorative frame applied thereto,

Fig. 2 is a vertical sectional view on the line 2—2 of Fig. 1 but with the thickness of the monograms greatly exaggerated,

Fig. 3 is an enlarged plan view of the rear face of the monogram and

Fig. 4 is a further enlarged view on the line 4—4 of Fig. 3 with the thickness of the monogram material and the adhesive material greatly exaggerated.

In Figs. 1 and 2, I have shown my improved monogram applied to a conventional metal cigarette case consisting of two hinged sections 10—10 which cooperatively form a pocket for the cigarettes when closed by snap latch 11. It is characteristic of such cases that they are slightly flexible and that at often times, all surfaces of them are slightly convex. Such slight convexity or such slight flexibility will not impair the security of attachment of my improved monograms. The monogram illustrated consists of three letters 12, encircled by a decorative ring or frame 13.

A typical letter is illustrated in Figs. 3 and 4. Such letter is etched from an extremely thin gauge bendable sheet metal stock say in the order of .005 to .015 inches in thickness and adhesive material such as a waterproof cement 14 is applied upon the back of the letter 12, in such a fashion that the adhesive material forms a ridge 15 following the entire periphery of the letter. Thus, when the adhesive is softened by the application of a suitable solvent and the letter is pressed against the supporting surface afforded by the cigarette case, the entire area of the letter which is confined within the peripheral ridge 15 will cooperate with the supporting surface to define an evacuated chamber giving a highly effective suction cup action.

While I may form a ridge of adhesive along the edges of the letters, it is within the scope of the invention to form criss-crossing ridges which will define a plurality of smaller suction cups or pockets, if desired. The monogram may be made of bright or dull metal stock or chrome metal finish or may be plated or enameled, the primary consideration being that the metal with its enamel or plating be extremely thin and where enamel or plating is used, it be of a nature which will not crack upon slight bending of the monogram which occurs when the monogram is secured to its slightly convex or slightly concave surface.

While it is within the scope of the invention to stamp monograms of sheet stock, I prefer to form the monograms by an etching process which in-

cludes the steps of painting the letters with lacquer upon a metal strip or sheet or otherwise covering the strip with an acid proof material of the same shape as the proposed letters, and then applying an acid to the metal sheet, the acid eating away the metal between the acid impervious portions thereof to form the letters. Subsequently the lacquer is removed.

It will be understood that the decorative frame 13 is formed of similar stock or similarly plated and that the adhesive on its rear surface is also arranged to form criss-crossing ridges or two annular ridges at the inner and outer edge of the ring. Such ridges cooperate to define an annular evacuated space, evacuation being effected by the manual pressure applied to the ring as it is pressed home against the support.

Due to the extreme thinness of the monogram and the extreme thinness of the adhesive, these letters when pressed against a surface, particularly one of contrasting color, give a highly realistic simulation of an inlay of precious metal. This is due to the fact that the edges of the letters are so extremely thin that the letters appear to lie flush with the surface upon which they are mounted.

By making these extremely thin letters of readily bendable metal, they will accommodate themselves to a slightly convex surface and they will not be dislodged by slight flexing of the surface upon which they are mounted.

The suction effect obtained is remarkable considering the thinness of the evacuated space. It is seemingly impossible to dislodge these letters by an edgewise thrust but if a very sharp instrument is applied under them and the seal afforded by the ridge of cement is once broken, the letters may be peeled from their supports with the greatest ease and the tell-tale marks on the support show clearly that the letters have adhered to the support only at their edges and that a real suction cup action has been had.

The particular adhesive material which is used is not in itself my invention and there are many types of non-water solvent, glues or cements which might be employed for the purpose, providing that they may be spread thinly enough on the backs of the letters. A typical adhesive material suitable for the purpose consists largely of collodion with a small amount of shellac and alcohol and a good solvent for such a cement is benzene.

I do not wish to be limited to any particular metal for the monograms although for simulating silver and gold, nickel silver and brass have proven highly satisfactory.

It will thus be seen that there is herein described an article in which the several features of this invention are embodied, and which article in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawing shall be interpreted as illustrative and not in a limiting sense.

Having thus described my invention what I claim as new and desire to secure by Letters Patent is:—

1. As a new article of manufacture, a flat backed monogram of hard material having a non-

water soluble adhesive material substantially completely covering its rear surface, a portion of said adhesive material forming a raised ridge around the periphery of the monogram whereby 5 to afford a suction cup effect when a solvent is applied to the cement and the monogram pressed against a supporting surface.

2. As a new article of manufacture, a flat metal monogram carrying a non-water soluble adhesive coating upon its rear face, said coating being so 10

applied that certain portions thereof form ridges cooperatively defining suction cups.

3. As a new article of manufacture, a metal monogram having an adhesive covering its rear face, the adhesive defining a raised peripheral ridge of adhesive material which not only secures the monogram to a support surface but which further forms a suction cup. 80
